FRENCH FRY BASKET

Grant M. Wilt, Columbus, Ohio, assignor to White Castle System, Inc., Columbus, Ohio, a corporation of Delaware

Filed Apr. 26, 1963, Ser. No. 74,627

Term of patent 14 years

(Cl. D81—10)

FIG. 1 is a top plan view of a French fry basket showing my new design;

FIG. 2 is a side elevational view;

FIG. 3 is an end elevational view;

FIG. 4 is a bottom plan view;

FIG. 5 is a side elevational view opposite to that of FIG. 2; and

FIG. 6 is an end elevational view opposite to that of FIG. 3.

The conventional wire mesh, as shown in the several figures of the drawings, is understood to continue throughout the plain unshaded areas of the body portion of the basket.

I claim:

The ornamental design for a French fry basket, substantially as shown and described.
